UNITED STATES PATENT OFFICE.

MARCUS T. GOLDSMITH, OF NEWARK, NEW JERSEY.

LOCKING DEVICE FOR FRAMES OF BAGS, PURSES, AND LIKE ARTICLES.

1,335,575.

Specification of Letters Patent. Patented Mar. 30, 1920.

Application filed January 26, 1920. Serial No. 354,118.

To all whom it may concern:

Be it known that I, MARCUS T. GOLDSMITH, a citizen of the United States, and a resident of Newark, in the county of Essex and State 5 of New Jersey, have invented a new and Improved Locking Device for Frames of Bags, Purses, and like Articles, of which the following is a full, clear, and exact description.

The object of the invention is to provide a 10 new and improved locking device for the frames of bags, purses and similar articles, and arranged to securely hold the frame members locked when in closed position with a view to prevent accidental or surreptitious 15 opening of the frame and abstraction of the contents of the bag, purse or similar article by unauthorized persons.

Another object is to provide a locking device which is simple and durable in construction, readily applicable to bag frames as 20 now generally constructed, and not liable to get easily out of order.

With these and other objects in view, the invention consists of certain novel features 25 of construction as hereinafter shown and described and then specifically pointed out in the claims.

A practical embodiment of the invention is represented in the accompanying drawings 30 forming a part of this specification, in which similar characters of reference indicate corresponding parts in all the views.

Figure 1 is a side elevation of the improved locking device as applied to the 35 frame of a hand bag, part of one of the frame members being broken out and the other frame member being shown in section;

Fig. 2 is a plan view of the same with the stems of the knobs of the locking device 40 shown in section;

Fig. 3 is an enlarged cross section of the same on the line 3—3 of Fig. 2; and

Fig. 4 is an enlarged sectional plan view of the same on the line 4—4 of Fig. 1.

The frame members 10 and 11 are pivotally connected with each other by pivots 12 to permit the frame members to swing into open or closed position. Under the top of the frame member 11 is arranged a spring 15 secured at one end by a lug 16 in place on the frame member 11. The free end of the spring 15 is provided with a keeper 17 provided with a knob 18, the stem 19 of which extends through an elongated slot 20 formed 55 in the top of the member 11. The keeper 17 is provided with an opening 21 to provide

a slightly beveled front member 22 adapted to be engaged by the beveled head 25 of a catch 26 secured to the frame member 10 at the inner side thereof, as plainly indicated 60 in Figs. 3 and 4. It will be noticed that by the arrangement described the catch 26 snaps into engagement with the keeper 17 on closing the frame members 10 and 11, to securely hold the frame members locked 65 when in closed position. When it is desired to open the frame members it is only necessary for the user to press the knob 18 to cause a downward swinging movement of the spring 15 whereby the keeper 17 is 70 moved out of engagement with the head 25 of the catch 26 to allow of swinging the frame members 10 and 11 into open position.

In order to lock the spring 15 and its keeper 17 and knob 18 against downward 75 movement to prevent accidental or surreptitious opening of the frame members 10 and 11, use is made of a locking arm 30 pivoted at 31 to the inner side of the frame member 11, and this locking arm extends 80 through a slot 32 formed in the top of the frame member 11, and the outer end of the arm is provided with a knob 33 under the control of the user for swinging the locking arm 30 into locking or unlocking position. The locking arm 30 is provided with a nose or projection 34 adapted to pass under the free end of the keeper 17 at the time the latter is in uppermost locking position relative to the head 25 of the catch 90 26. It will be noticed that when the nose 34 is in this locking position, as shown in the drawings, the spring 15 and its keeper 17 and knob 18 are held against downward movement and consequently the frame members 10 and 11 are held in locked position.

When it is desired to unlock the keeper 17 and its spring 15 and knob 18 then the user takes hold of the knob 33 and swings the locking arm 30 over to the right into the 100 position shown in dotted lines in Fig. 1 whereby the nose 34 moves out from under the keeper 17 and hence the latter is unlocked, and the spring 15 can now be swung downward on the user pressing the knob 18 105 for disengaging the head 25 of the fixed catch 26, as above explained.

In order to hold the spring 15 and its keeper 17 against lateral movement, use is made of guideways 40 and 41, of which the 110 guideway 40 is in the form of a pin depending integrally from the under side of

the top of the frame member 11 and extending through the opening 21 in the keeper 17. The other guideway 41 is formed integrally on the inner face of the frame member 11 and the back of the keeper 17 slidably abuts the guideway 41. By the arrangement described an exceedingly strong and durable construction is provided to guide the keeper 17 in its up and down movement and to hold the catch 26 in firm engagement with the keeper thus insuring a tight closing of the frame members 10 and 11. It will also be noticed that by the use of the spring arm 30 the keeper 17 is locked against movement at the time the fixed catch 26 engages the keeper to securely hold the frame members 10 and 11 locked against accidental or surreptitious opening by unauthorized persons.

20 Having thus described my invention, I claim as new and desire to secure by Letters Patent:—

1. In a hand bag, purse or similar article, a pair of frame members hinged together, 25 a spring attached at one end to one of the frame members and provided at its free end with a keeper, a catch fixed on the other frame member and adapted to engage the

said keeper to lock the frame members in closed position, and a locking arm pivoted 30 on the said frame member carrying the spring, the said locking arm having means engaging the said keeper to hold the latter against movement at the time the catch engages the keeper to prevent unlocking and 35 opening of the frame members.

2. In a hand bag, purse or similar article, a pair of frame members hinged together, a spring attached at one end to one of the frame members and provided at its free end 40 with a keeper having a slot, a catch fixed on the other frame member and adapted to snap into engagement with the slot, a guide pin fixed on the said frame member carrying the spring, the said guide pin extending through the said keeper slot, and a locking arm pivoted on the said frame member carrying the spring, the said locking arm having a knob extending to the outside of the said frame member, the said 45 locking arm having a nose adapted to engage the under side of the said keeper to lock the latter against downward movement and thus prevent disengagement of the catch from the keeper.

MARCUS T. GOLDSMITH.
